UNITED STATES PATENT OFFICE.

JOSEPH L. HALL, OF CINCINNATI, OHIO.

MEANS FOR FASTENING THE DOORS OF SAFES, &c.

SPECIFICATION forming part of Letters Patent No. 398,609, dated February 26, 1889.

Application filed June 5, 1888. Serial No. 276,137. (No model.)

To all whom it may concern.

Be it known that I, JOSEPH L. HALL, of Cincinnati, in the county of Hamilton and State of Ohio, have invented certain new and useful Improvements in Means for Fastening the Doors of Safes, Vaults, &c., of which the following is a specification.

My present invention relates to means for securely fastening the doors of safes, vaults, jails, and similar inclosures; and the invention consists in a series of bolts arranged to lock and unlock one or more movable bars or bolts, which are made to interlock with the door when closed, and in combining there- with mechanism by which the series of locking-bolts shall be made to operate simultaneously in the locking or unlocking, and also in combining with said bolts and mechanism a time-lock and means for automatically un- locking the parts at a predetermined time, as hereinafter more fully described.

Figure 1 is an inside view of the door and surrounding frame of a safe, vault, or similar receptacle. Figs. 2, 3, 4, and 5 are views of portions shown more in detail, Figs. 4 and 5 being end or section views taken on the line y y of Fig. 1. Figs. 6 and 7 represent the time-lock with the levers for connecting it with the operating mechanism enlarged, the former showing them locked and the latter un-locked.

My present invention is designed to be used in connection with safes, vaults, &c., which have set in the stationary jambs which surround the door a movable bar in the form of a bolt or cylinder having a groove along one side, in which a projecting flange on the edges of the door engages automatically as the door is closed, and which, being fully described in a separate application filed simultaneously herewith, and to which reference is made, need not be described herein, except so far as may be necessary to illustrate the present invention. In Figs. 4 and 5 these movable bars or bolts C are shown in position as they will be when the safe or vault is built, Fig. 5 showing the flanges b of the door B begin-ning to engage with them as the door is being closed, while Fig. 4 shows them with the door completely closed, and showing how they hold the door by engaging with the projecting flanges b thereof.

My present invention consists of means for locking and unlocking these movable bars or bolts C, and thereby the door of the safe or vault. To accomplish this, I make use of a series of locking-bolts, L, as shown more clearly in Figs. 2 and 3. The locking-bolts L, which may be round, square, or oblong in cross-section, are set in holes in the inner walls of the frame A, directly opposite the movable bars or bolts C, there being a hole or recess, P, in the bolt C, for the bolts L to engage in, and thus prevent the bolts C from being turned until said locking-bolts L are withdrawn. Each of the bolts L is provided with a stem having a knob or enlargement on its outer end, and each is provided with a spring, t, preferably incased in the hole surrounding the stem, arranged to press the bolt inward and cause it to automatically enter the hole P whenever the movable bar or bolt C is turned to the position shown in Fig. 4 by the closing of the door. In Fig. 2 the bolts C and L are shown in the locked position, and in Fig. 3 in the unlocked position.

In Fig. 1 I have shown but one locking-bolt L as being applied to each of the movable bars or bolts C; but it is obvious that more may be applied, if desired. As these locking-bolts are within the safe or vault, it is necessary to provide means for withdrawing them when it is desired to unlock the door, and for this purpose I pivot near each bolt L an elbow-lever, I, as shown in Figs. 2 and 3. One arm, n, of each of these levers is slotted and arranged to engage the stem of the locking-bolt L, so that by tipping the lever I the bolt L will be withdrawn, as clearly shown in Fig. 3, the other arm, o, of the lever projecting out at a right angle from the face of the wall, as shown.

In order to withdraw the locking-bolts L simultaneously all around, I connect the arms o of each by means of a series of sliding rods, R, as represented in Fig. 1, these rods R being connected at their ends by bell-crank levers k, mounted on a stud or pivot, h, each rod R having secured to it a clip or plate, w, provided with a hole, in which the arms o of the elbow-levers I engage. By this arrangement it will be seen that when an endwise movement is imparted to any one of the rods R they will all be made to move longitudi-

nally, and acting on the arms *o* of the elbow-levers I will tip them, thereby simultaneously withdrawing all the locking-bolts *L*, and thus unlock the movable bars or bolts *C*, 5 when, of course, the door is free to be opened.

In order to move the rods *R*, and thereby the bolts *L*, I attach to one of the short vertical rods *R* a weight, *W*, sufficient when released to move all the rods and elbow-levers 10 *I* and compress the springs *t* and withdraw the bolts *L*, this weight being preferably held by guides at its sides, as shown in Fig. 1.

The system of rods *R*, *I* connect with a suitable time-lock, *T*, in any convenient manner, 15 so that the time-lock will release the weight at such time as the lock may be set for, when, of course, the weight will cause the rods *R* to move, and thereby withdraw the locking-bolts *L*, as above described.

20 As there are many styles or forms of time-locks, it is obvious that the connection of the time-lock with the operating-rod *R* may be made in a variety of ways, depending on the style of lock used. I prefer to use one of the 25 various forms of locks heretofore patented to me, and in which there is a depending latch or lever, *l*, arranged to engage with the long arm of a hook-shaped lever, *m*, and which at its short end engages with the long arm of a similar 30 lever, *i*, the short hook-shaped arm of which engages with a stud or projection, *p*, secured to the short vertical rod *R*, as shown in Fig. 1 and more clearly in Figs. 6 and 7. The only object of this arrangement of levers between the time-lock and the rods *R* is to support the weight *W* without creating such a strain or friction as to prevent the timer 35 from tripping or moving the latch *l* at the proper time. Any other connecting devices 40 which will accomplish the same result may be used instead, and when a different style of time-lock is used the connection may be varied to suit, the only requirement being that they shall be such as will hold the weight suspended until the proper time for opening the 45 door arrives, and then be released by the time-lock. With the parts thus arranged, it is only necessary to set the time-lock, and, before the door is closed, raise the weight and 50 connect its rod *R* with the time-lock, as described, and then shut the door, which will turn the movable bars or bolts *C* to the position shown in Fig. 4, which will bring the 55 holes *P* in said bolts opposite the ends of the locking-bolts *L*, which will be forced into the holes by the springs *t*, and thus the door will be securely locked, and will be so held until, at the predetermined time for which the time-lock may have been set, it will release the 60 weight, which, operating to withdraw the locking-bolts *L*, as previously described, will automatically unlock the door.

When a time-lock is thus used in connection with the locking-bolts and their operating 65 mechanism, all of which are within the safe or vault, it will be seen that there is no hole or opening of any kind in the door or the jambs

or walls for the admission of explosives, or by which the exterior is in any way weakened.

70 While I have shown the locking-bolts as being connected and operated by a series of rods and elbow-levers, it is obvious that other mechanical devices may be substituted for them and be made to produce the same result, and hence my invention is not limited to the use 75 of these special devices. So, too, it is obvious that a spring may be substituted for the weight *W*.

It is obvious that the time-lock and its connecting-levers may be located at the opposite 80 side or at top or bottom, it only being necessary that they shall be so connected with the rods *R* as to hold the weight suspended until released by the time-lock at the time set.

85 While I prefer to use a time-lock in connection with these movable bars or bolts *C*, it is obvious that they may be locked by a series of sliding bolts operated by a handle in the usual manner, these in turn being secured by a permutation-lock; but that would necessitate making holes in the door for the handle and for the spindle of the dial, and hence 90 would not be so secure, and yet in some of the smaller or cheaper forms of safes or vaults it may be desirable.

95 It is impossible without undue prolixity to describe all the various modifications necessary to connect the locking-bolts and their operating mechanism with all the forms or styles of time-locks known; but the foregoing description will enable a mechanic skilled in the art to do so without difficulty.

Having thus fully described my invention, what I claim is—

1. The combination, in a safe, vault, or other 105 inclosure having a door and jambs, of the movable bars or bolts *C*, located in one of said parts, and a projection, *b*, on the other of said parts, a series of locking-bolts, *L*, and mechanism, substantially such as described, for 110 connecting and operating said locking-bolts, whereby they can be simultaneously withdrawn to unlock the movable bars or bolts.

2. The combination, with a door and its 115 jambs, of the movable bars or bolts *C* set therein, a series of locking-bolts, *L*, connected by mechanism for simultaneously withdrawing the locking-bolts, and a weight, *W*, arranged to operate the same when released, 120 substantially as described.

3. In combination with the movable bars or bolts *C*, set in the jambs or door, a series of locking-bolts, *L*, with their connecting and operating mechanism, and a time-lock, *T*, adapted to be connected to the locking-bolt 125 mechanism and to be disconnected therefrom by the action of the time-movement, substantially as and for the purpose set forth.

4. In combination with one or more movable bars or bolts, *C*, arranged and operating 130 as described, a corresponding number of locking-bolts, *L*, connected to a sliding bar, *R*, having a weight, *W*, attached thereto, a time-lock, *T*, and the intermediate pivoted levers

m and *i*, all arranged for joint operation substantially as shown and described.

5. In combination with the movable bars or bolts *C*, the bolts *L*, provided with springs to cause them to automatically engage with the movable bars or bolts *C*, a weight arranged to withdraw said locking-bolts when released, and a time-lock arranged to hold said weight and automatically release the same at the

time set, substantially as and for the purpose 10 set forth.

In witness whereof I hereunto set my hand in the presence of two witnesses.

JOSEPH L. HALL.
